FIREARM WITH EXCHANGEABLE BARREL

Friedrich Linder, Dusseldorf, Germany, assignor
to Rheinische Metallwaaren-und Maschinen-
fabrik, Dusseldorf, Germany, a corporation of
Germany

Application November 27, 1933, Serial No. 699,989
In Germany April 10, 1933

3 Claims. (Cl. 42—76)

The invention relates to firearms of the exchangeable barrel type. An object of the invention is to provide a safety device which automatically makes it impossible for a shot to be discharged if the barrel is incorrectly mounted in the weapon, thereby avoiding the result of a faulty mounting, which, on a shot being fired, would interrupt the functioning of the weapon and cause serious damage. In such cases, which are particularly liable to occur when the barrel of a machine gun is changed while it is in actual use or during assembly of large calibre machine guns which have been taken to pieces for purposes of transport, the safety member according to the invention co-operates with a housing to jam the barrel and breech casing in a position preventing opening of the breech, which renders it impossible for the gun to be loaded. The gun crew's attention is thus imperatively directed to the fact that the barrel has been incorrectly inserted, and before the gun can be fired at all, the gun crew must bring the barrel into a satisfactory state of coupling.

The drawing illustrates a typical embodiment of the invention and shows by way of example a large calibre automatic gun having a sliding barrel, bolted breech, and a bayonet joint type of barrel connection; in a particularly advantageous form of construction the locking member which secures the bayonet connection against detachment at the same time forms the new automatic safety device.

Fig. 1 shows a longitudinal section of the middle part, with the barrel connection of the gun, and

Figs. 2 and 3 show cross-sections at the plane of the safety device and the bayonet connection on the lines I—I, II—II of Fig. 1 respectively.

The barrel *a* of the gun is adapted to be removed, in known manner, from the housing of the gun, either by moving it forwardly, or backwardly together with the breech casing *b* and the breech block *d* which is bolted thereto.

The breech bolting, which is not shown in the drawing, is of the type usually found in such guns, wherein the breech for ejecting a fired cartridge and for loading does not open until a definite distance of recoil has been traversed, which distance it covers together with the breech casing *b* and the barrel *a* in closed and bolted position.

For its connection the barrel is provided on the rear end with three coaxial series of bayonet lugs *a* distributed over its periphery, which lugs when the barrel has been properly inserted, en-

gage behind corresponding lugs *b* on the breech casing *b*, which surrounds the barrel over a considerable length near the breech and closes it. To the right (Fig. 1) the bayonet lugs *a*, which are for instance of the same thickness throughout, there is provided a thicker projection *a'* which engages in a correspondingly wide recess *b'* in the breech casing. The design of the projections and grooves is such as to prevent the barrel after it has been inserted axially in the breech casing *b*, from turning into bolting position unless it has been inserted to the required depth at which it abuts the shoulder *b*. In this position, and after it is turned, all the lugs *a* interlock with the lugs *b* and, therefore, when subjected to firing stress, the coupling possesses the requisite strength and firmness.

In the coupling position shown in the drawing, the projection *e* of a locking member *e* mounted in the breech casing so as to be capable of bending upwardly, engages in a safety notch *a* in the barrel, in order that the latter cannot be turned accidentally out of the position attained by it.

When the locking member *e* is sunk in the outer wall of the breech casing *b*, the latter with the barrel and the breech block can be displaced in the housing *c*, towards the right (Fig. 1). Barrel *a*, breech casing *b* and breech *d* can then be withdrawn in the usual manner for loading the gun and after a certain length of recoil the breech mechanism, not shown and of the kind usual in guns of this type, unlocks the breech *d* so that it can be opened and a cartridge inserted in the cartridge seating of the barrel *a*. If, however, the bayonet coupling has not been properly engaged, the projection *e* on the locking member will rest on a reduced portion *a* of a collar *a* of the barrel, causing the shaft *e* of the locking-member to bend flexibly outwards. Thereby the part thereof which protrudes forwardly from the housing *c* tends to jam in a recess *c* in the housing, with the result that the breech casing cannot be moved to the right to open the breech, and the gun cannot be loaded and also cannot be fired because the breech mechanism frees the breech *d* after the barrel *a* and breech *d* have together travelled back a certain distance.

The locking member *e* is flexibly gripped in the rear portion of the breech casing groove *b* which is of dovetailed form from the point *b* towards the breech, and is secured against longitudinal displacement by the engagement of its lower projection *e* in an opening in the base of the groove. The shoulders *a*, *a* at the ends of the reduced

portion a_3 of the collar a_4 of the barrel, in cooperation with the locking member e , limit the turning of the barrel both in the non-assembled position and when the bayonet connection has 5 been completely made. In order to remove the barrel from the breech casing the front part of the locking member is raised by hand and disengaged from the barrel notch a_2 . On the insertion of the barrel into the breech casing, owing 10 to the oblique under surface of its front end, the locking member is guided automatically over the projecting barrel members.

I claim:

1. In a firearm, a housing, a breech casing 15 slideable in the housing, a barrel, a bayonet connection between the barrel and the casing permitting removal of the barrel therefrom, and flexible locking means having projections engaging recesses in the barrel and breech casing, said means 20 being slideable along with the barrel and breech casing in the housing when the barrel is properly mounted and in case of improper mounting said means being bent by incomplete engagement of one of its projections in the corresponding recess 25 into a position causing jamming of the barrel and breech casing in the housing in a position preventing opening of the breech, and said bayonet connection between the barrel and breech casing comprising a plurality of interrupted collars and separating grooves on each part, the 30 dimensions of said collars and grooves being such that the barrel can be turned to lock the connection only when all the collars and grooves are in correct registering relationship.
- 35 2. In a firearm having a housing and a recoil

system mounted therein comprising a barrel, a breech casing to which the barrel is removably connected, and a breech block which remains closed during the first portion of the recoil; the arrangement of connections between the barrel 5 and the breech casing engaging each other over a fixed axial length, a locking member engaging said barrel and breech casing and slideable freely therewith in the housing when the barrel and breech casing are interconnected over said fixed 10 axial length, and means effective upon said locking member only when the barrel is connected with the breech casing over an axial length other than the said fixed length to cause said locking member to arrest the recoil system in said first 15 portion of the recoil.

3. In a firearm having a housing and a recoil system mounted therein comprising a breech casing, connections for removably mounting the barrel in the breech casing, said connections being 20 fully engaged by predetermined rotary and axial movements of the barrel and casing relatively to each other, and a breech block which remains closed during the first portion of the recoil; the arrangement of a locking member engaging said 25 barrel and breech casing and slideable freely therewith in the housing when the barrel and breech casing are properly interconnected, and means effective upon said locking member only upon engagement of said connections by other than 30 said predetermined rotary and axial movements to cause said locking member to arrest the recoil system in said first portion of the recoil.

FRIEDRICH LINDER. 35
